DESIGN FOR AN AIR CONDITIONING CONTROL PANEL

Frederick A. Selje, Grosse Pointe, Mich.

Application October 22, 1936, Serial No. 65,422

Term of patent 7 years

To whom it may concern:

Be it known that I, Frederick A. Selje, a citizen of the United States, residing at 286 Rivard Boulevard, in the city of Grosse Pointe, county of Macomb, and State of Michigan, have invented a new, original, and ornamental Design for an Air Conditioning Control Panel, of which the following is a specification, reference being had to the accompanying drawing forming a part thereof, in which:

Fig. 1 is a plan view of a control panel showing the new design.

Fig. 2 is a side elevational view, partly in section, taken on the line 2—2 of Fig. 1.

Fig. 3 is a horizontal sectional view taken on the line 3—3 of Fig. 1.

I claim:

The ornamental design for an air conditioning control panel substantially as shown.

FREDERICK A. SELJE.
